(57) **CLAIM**

The ornamental design for a stirring unit for a cooked rice processing machine, as shown and described.

DESCRIPTION

FIG. 1 is a top, front, right side perspective view of a stirring unit for a cooked rice processing machine, showing the new design;

FIG. 2 is a bottom, front, left side perspective view thereof;

FIG. 3 is a front view thereof;

FIG. 4 is a rear view thereof;

FIG. 5 is a top plan view thereof;

FIG. 6 is a bottom plan view thereof;

FIG. 7 is a left side view thereof;

FIG. 8 is a right side view thereof; and,

FIG. 9 is a top, front, right side perspective view thereof installed in a cooked rice processing machine.

In FIG. 9 broken lines depict environmental structure, namely a cooked rice processing machine, which forms no part of the claimed design.

1 Claim, 7 Drawing Sheets
